UNITED STATES PATENT OFFICE.

WILLIAM D. WATSON, OF CHICAGO, ILLINOIS.

WINDOW.

SPECIFICATION forming part of Letters Patent No. 702,754, dated June 17, 1902.

Application filed October 4, 1901. Serial No. 77,575. (No model.)

To all whom it may concern:

Be it known that I, WILLIAM D. WATSON, a citizen of the United States, residing at Chicago, in the county of Cook and State of Illinois, have invented certain new and useful Improvements in Windows, of which the following is a specification.

This invention relates to improvements in windows, and more particularly to fireproof-
10 windows of that class which have their frames and casings made of sheet metal.

The object of the invention is to provide an improved construction for securing the glass in place in the windows of this character; and to this end it consists in the matters herein set forth, and particularly pointed out in the appended claims.

In the drawings, Figure 1 is a front elevation of a metal window constructed in accordance with my invention and comprising a lower stationary and an upper pivoted or swinging sash, to both of which my improvements are applied. Fig. 2 is a sectional side elevation thereof. Fig. 3 is a top plan section taken through the stationary sash on line 3 3 of Fig. 1. Fig. 4 is a top plan section taken through the swinging sash on line 4 4 of Fig. 1. Fig. 5 is a fragmentary perspective view indicating the manner of inserting the glass in the sash. Figs. 6, 7, 8, and 9 are top plan sections further showing the manner of inserting the glass in the sash. Figs. 9^a and 10 are reverse perspective details better showing the construction at the base of the 35 middle bar of the sash. Fig. 11 is a detail in sectional elevation showing the manner in which the middle bar and clamping-bar are connected to the casing at their upper ends. Fig. 12 is a top plan detail thereof, taken on line 12 12 of Fig. 11. Fig. 13 is a perspective detail showing the formation of the window-casing at its point of juncture with the middle clamping-bars. Fig. 14 is a perspective detail of the upper end of the clamping-bar. Fig. 15 is a side elevation of the clamping-bar as a whole. Fig. 16 is a perspective detail showing the location of the screw-plates in the middle bars. Fig. 17 is a similar view showing the relative positions of the middle 40 and clamping bars when placed in position with the glass between them. Fig. 18 is a similar view showing the manner of securing the clamping-bar in place by clamping-screws engaging the screw-plates in the middle bar.

In said drawings, A designates the rectangular outer casing of the window which is designed to be built into the wall of the building B in the usual manner. This casing is herein shown as divided by a transverse bar *a* into upper and lower sections, of which the upper section is in this instance provided with a swinging sash C, while the sash D of the lower section is made fixed or stationary. It will, however, be understood that in so far as the present invention is concerned it is immaterial whether the window-casing comprises one or more sections or whether the sash of any section is fixed or is arranged to slide or swing, my improvements being equally applicable in either case.

Extending around the inner margin of each sash is a groove 1, made of suitable width to receive the edges of the panes of glass G and of a depth desirably about equal to its width, except along the upper edge of the sash, where the groove takes the form of an open slot 2, into which the glass may be thrust considerably farther than the distance which it normally occupies when in place, Figs. 2 and 5.

The glass G for each sash is provided in a plurality of panes—in this instance two—the aggregate width of which is made somewhat less than the extreme inner width of the sash from the bottom of the groove 1 on one side to the bottom of the same groove on the other. This permits the glass to be inserted by proceeding in the manner indicated in Figs. 5 to 9, inclusive. The upper edge of the first pane is slipped angularly up through the slot 2, as shown in Fig. 5, and the whole pane is then swung into a vertical position and slipped down until its lower edge enters the groove 1 at the bottom of the sash. The pane then occupies a position such as is indicated in Fig. 6 and can be slipped sidewise until one of its lateral edges enters the groove 1 at the side of the sash, as shown in Fig. 7. This leaves a space between its other lateral edge and the other side of the sash wide enough to receive the second pane, which is then inserted in the same manner as the first pane until it occupies the position shown in Fig. 8, whereupon it is moved sidewise away from the first pane until its lateral edge enters the groove 1 on the other side of the sash, as shown in Fig. 9. The glass is then secured in this position, as follows: Midway between its sides the sash is provided with a vertical

bar 3, located in front of the groove 1, with its rear face in the same plane as the front edge of said groove or in line with the front surface of the inserted glass. This bar covers the adjacent edges of the two panes of glass on their front sides and affords a ledge against which these inner edges of the glass rest. Operating in conjunction with this middle sash-bar 3 is a clamping-bar 4, having forwardly-projecting flanges 5, which enter between the panes, so as to prevent their lateral movement, and lateral flanges 6, which project back to the glass and hold it firmly against the front bar 3. This clamping-bar is herein shown as secured in place by screws 7, which extend through the bar into screw-plates 8 in the front bar 3 and by turning up which the glass may be held between the clamping-bar and front plate as tightly as desired. This clamping-bar is put in place after the panes have been inserted and moved laterally into their final positions, as shown in Fig. 9, and the tightening of its screws 7 completes the glazing operation.

In the case of the lower or stationary sash the manner of applying the clamping-bar is somewhat similar to the first operation of inserting the glass—that is to say, its upper end 9, which is extended above its flanges 5 and 6, is thrust angularly up through an aperture 10 in the top of the sash, after which the bar is swung forward into vertical position against the glass and then slipped down until its lower end 11, which is extended below its flanges 5, enters a groove 12, formed parallel and adjacent to the groove 1 in the bottom of the sash. This brings the screw-holes in the bar 4 into register with the threaded holes in the plates 8 of the bar 3 and enables the screws 7 to be inserted and turned up to clamp the glass in position, as above described. The bar 3 of the lower sash is herein shown as cut out at 13 to fit over the outer angle of the sill or bottom of the sash and as secured thereto by a rivet 5' or the like, while at its upper end it is permanently locked within the top of the sash by extending up through an opening 14 thereof. In case of the upper or swinging sash this bar is shown as simply riveted to the top and bottom of the sash, while its clamping-bar is secured in place only by the screws 7. In either case, however, the bar 3 will ordinarily be a permanent part of the sash.

One great advantage of the construction described is that it enables the window to be glazed from the inside of the building and does not require any attention or manipulation from without, as is commonly necessary in fireproof windows of this character. Windows so constructed may, furthermore, be made of any desired width and arranged to contain as many panes of glass as may be necessary to glaze the desired width of the sash without regard to the width of the panes, since it is only necessary to provide as many additional bars 3 and 4 as are needed in clamp-

ing the adjacent edges of each pair of panes. Obviously many changes may be made in the details of the construction shown without departure from the broad spirit of the invention 70 claimed.

I claim as my invention—

1. In a window, the combination with a plurality of panes of glass, of a sash grooved to inclose said panes of glass, a bar fixed to and extending across the sash in front of the plane of the groove and past which the panes may be slid laterally to introduce them to and withdraw them from the lateral portions of the groove, a clamping-bar interposed between the panes when slid into the side grooves and bearing against their adjacent edges opposite to the fixed bar, and means for detachably securing the clamping-bar in place, substantially as described. 85

2. In a window, the combination with a plurality of panes of glass, of a sash grooved to inclose said panes of glass, a bar fixed to and extending across the sash in front of the plane of the groove and past which the panes may be slid laterally to introduce them to and withdraw them from the lateral portions of the groove, a clamping-bar interposed between the panes when slid into the side grooves and bearing against their adjacent edges opposite to the fixed bar, and clamp-screws detachably securing the clamping-bar to the fixed bar, substantially as described. 90

3. In a window, the combination with a plurality of panes of glass, of a metal sash grooved to receive said glass, the upper portion of said groove being an open slot through which the glass may be abnormally projected, a bar extending across the sash in front of the groove and against which the adjacent edges of the panes bear on their front sides, a clamping-bar interposed between the panes and bearing against their adjacent edges on their rear side, and means for detachably securing the clamping-bar in place, substantially as described. 100

4. In a window, the combination with a plurality of panes of glass, of a metal sash grooved to receive said glass, a bar extending across the sash in front of the groove and against which the adjacent edges of the panes bear on their front sides, a clamping-bar interposed between the panes and bearing against their adjacent edges on their rear sides, screw-plates secured in the cross-bar, and screws passing into the screw-plates to secure the clamping-bar detachably in place, substantially as described. 115

In testimony that I claim the foregoing as my invention I affix my signature, in presence of two subscribing witnesses, this 1st day of October, A. D. 1901.

W. D. WATSON.
